UNITED STATES PATENT OFFICE.

ANATOLE C. REINY, OF WASHINGTON, DISTRICT OF COLUMBIA.

FIBER-CLEANING MACHINE.

Application filed May 22, 1920, Serial No. 383,510. Renewed February 9, 1924.

To all whom it may concern:

Be it known that I, ANATOLE C. REINY, a citizen of the United States, residing at Washington, District of Columbia, have invented certain new and useful Improvements in Fiber-Cleaning Machines, of which the following is a specification.

My invention relates to machines for treating long fiber plants, in order to cleanse the fibers of the matter associated therewith by nature that must be gotten rid of in order that they shall be marketable and suitable for use in commerce and the arts.

It has for its object to produce a machine of this kind that will thoroughly separate and clean the fibers without breaking or injuring them and that possesses novel and important features which I will point out in the following specification and claims.

In the accompanying drawings I have illustrated a machine embodying my invention especially adapted to treat tropical plants, such as the leaf stems of the banana and abaca, pita floja, henequen or sisal and other grasses, and plants or parts of plants of which those just mentioned are typical. I shall assume the machine is intended particularly for treating abaca.

Fig. 1 is a side elevation of the machine and Fig. 2 is a top plan view thereof, many of the details being omitted, owing to the small scale on which these views must be made, and the showing being largely diagrammatic.

Fig. 3 is a longitudinal sectional view of the feeding end of the machine;

Fig. 4 is a longitudinal sectional view of the delivery end of the machine;

Fig. 5 is a transverse sectional view;

Fig. 6 is a plan view of one of the fiber clamps;

Fig. 7 is an end view of one end of a fiber clamp;

Fig. 8 is a transverse sectional view of one of the fiber clamps;

Fig. 9 is a transverse sectional view illustrating the mechanism that controls the starting of a fiber clamp on its course through the machine;

Fig. 9^a is a sectional view on a larger scale than Fig. 9 and somewhat more in detail showing only the mechanism at one side of the machine.

Fig. 10 is a side view of the mechanism shown in Fig. 9^a.

Figs. 11, 12, 13 and 14 are detail views of

parts of the mechanism shown in Figs. 9, 9^a and 10;

Fig. 15 is a top plan view of the delivery end of the machine;

Fig. 16 is a side elevation with parts broken away and in longitudinal section showing the upper portion of the delivery end of the machine;

Fig. 17 is a longitudinal sectional view of mechanism shown in Fig. 16;

Fig. 18 is a transversal sectional view taken on the line 18—18 of Fig. 16 showing one side only of the machine;

Fig. 19 is a transverse sectional view on the line 19—19 of Fig. 16 showing one side only of the machine;

Fig. 20 is a side elevation, largely diagrammatic, illustrating the machine embodying my invention combined with a mobile support; and

Fig. 21 is a plan view of the apparatus shown in Fig. 20.

The machine illustrated in the drawings as embodying my invention is in its general features similar to that illustrated in Patent #1,238,310 to C. F. Logan, assignor to Fiber Products Corporation. Therefore many features that are fully described in that patent and are hence known to the public need not herein be illustrated or described in detail.

Referring now to the drawings it will be seen that the frame of the machine is formed of sections 2 that are easily separable one from the other, so that the complete machine may be formed of a greater or less number of these as may be required; and further facilitating the disassembling of the machine into small sectional units that may be easily shipped or stored. A conveyor 3 substantially coextensive with the frame, directs the material being treated through the machine. It preferably consists of a pair of endless sprocket chains engaging with suitable supporting and driving wheels arranged to drive the chains in unison and to insure that corresponding links in the two chains shall be directly opposite to and in alignment with each other transversely. The conveyor is represented as being driven from a shaft 5 receiving power from any suitable source.

Along the working run of the conveyor are located the several mechanisms that treat and clean the fiber of which there may be more or less, as may be required by the

nature of the material being operated upon. These fiber treating means are arranged in groups substantially as illustrated and fully described in the aforesaid Patent #1,238,310. 5 Each group or set of fiber treating means contains at least two elements, one of which is positively rotated and serves as the active element that acts upon the material being treated, while the other element serves 10 as a support for the material. Associated with the fiber treating means are driven rollers that operate to assist in feeding the material through the machine, so that the strain thereon required to advance it does 15 not have to be applied entirely through the leading end thereof but is distributed along its length.

Referring to Figs. 1 and 2 which illustrate a typical machine, the first fiber treating set of devices, located at position I, may well consist of a supporting roller and an opposed positively driven cylinder carrying knives or skiving tools adapted to act upon the material for the purpose of removing 20 therefrom a large portion of its cellular pulpy substance without disturbing the valuable fibers. In the arrangement shown the skiving element is located below, and the supporting roller above the path of the material being treated, although this arrangement might be reversed. At position 25 II may be located devices for scutching the material, if this action be desirable, these consisting of a rotated lower scutching device and an opposing upper cylindrical support. Between the positions I and II are driving rollers such as have been referred to. The sets of fiber treating devices at 30 positions III, IV, V and VI may be adapted to brush and comb the fibers removing from them the pulpy and other undesirable material, a sufficient number of sets of such cleaning devices being employed to leave the fibers clean and in condition for use 35 after being properly dried. The active cleaning elements of these groups may be brushes with metallic bristles. Some of these brushes are disposed above the path along which the material travels, as indicated at 40 positions III and V, while others may be below such path, as indicated at positions IV and VI. With each brush is associated an opposing rotating cylinder that serves 45 as a support for the material while it is being brushed and cleaned.

The clean fibers at sections 7 and 8 of the machine are dried, being here subjected to currents of air which may if desired be heated. Arriving at position IX the fibers 50 are supposed to be clean and dry and ready to pass out of the machine. Here the clamps employed to hold the fibrous material and connect it with the conveyor 3, as will be later described, are released and separated 55 from the fibers, and returned to the head

of the machine, by means of a conveyor 4 to which they are delivered through a chute 6, while the cleaned fibers pass to a conveyor 7 from which they are finally discharged at the position X.

A simple arrangement for driving the several parts of the apparatus is diagrammatically represented in Figs. 1 and 2, where the directions in which the several parts move are indicated by arrows. The conveyor 3 receives its power directly from the shaft 5 and is directed by guide wheels, as represented. A crossed belt 8 transmits power from the shaft 5 to a shaft 9, that is connected by a belt 10, with a shaft of 60 one of the active fiber-treating elements that is located above the path of the material, in the present instance the brush element of group III. This shaft through suitable gear wheels and belting 12 drives the other 65 active cleaning elements that are located above the path of the material. This insures that these cleaning elements shall so rotate that their acting portions move in a direction the reverse of that followed by 70 the material as it travels through the machine. The gear relations are such that the peripheral speeds of the fiber-cleaning devices are greater than the speed of advance 75 of the material. These speed ratios may be changed to suit conditions due to the character of the material being treated. The fiber-treating devices located below the path of movement of the material are connected and driven through another train, including 80 a belt 13 connecting the main shaft 5 with the shaft of one of the active fiber-treating elements, as for instance, that at position VI, and this, in turn is connected, 85 through gearing and belts 16, with the other fiber-treating devices that are located below the path of the material. The belt 13, as will be seen, is not crossed, so that it operates 90 to drive the rotating fiber-treating devices which it drives in a direction against the forward movement of the material through the machine, and its speed ratio is such that the peripheral speed of each of 95 these cleaning devices is greater than the speed of advance of the material.

The several sets of feed rollers 20 that cooperate with the main conveyor 3 to advance the material through the machine are driven by belts 17. These receive power 100 from a shaft 18, driven from the shaft 5 by crossed belt 19. Another shaft, 22, connected with the shaft 18 by a crossed belt 24, drives the return conveyor 4 directly, and the conveyor 7, through a crossed belt 25.

Mechanism is provided at the feed end 105 of the machine for timing the connection of the fiber clamps with the conveyor 3, as will be later described; and this is driven by a crossed belt 27.

The driving gear arrangement described is typical and may be varied within a wide range as circumstances may require. That illustrated gives to the several rotating parts 5 the proper direction of movement and the proper relative speeds.

With this somewhat general description of the machine I will proceed to set forth its features more in detail, referring particularly to the detail views of the drawings.

Each of the sprocket chains of the conveyor 3 is supported and directed by guides 15 suitably arranged in the frame of the machine, and parallel with these guides, 20 preferably outside thereof are rails 14 upon which run the clamps 32 employed to grasp the masses of fiber being cleaned and lead them through the machine. The sets of feed rollers 20 consist of the upper rollers 23 and the lower rollers 35. But one of each pair of feed rollers need be positively driven, the other receiving its motion by friction from such driven roller, and I have represented the shafts of the lower feed rollers 35 as having secured to them sprocket wheels 39, Fig. 18, that are engaged by the chains or driving belts 17, already referred to, for driving these elements of the machine. The fiber treating and cleaning groups of devices each 30 comprise a rotating cylinder 36 and a rotating element 29 opposed thereto and serving as the active fiber cleaning member. This part 29 may be of one construction or another, as the nature of the material being treated may demand, and as may be called for by its position in the machine. Thus the elements 29 toward the head or feed end of the machine may be cylindrical skivers, while those further advanced toward the delivery end of the machine are usually brushes 40 armed with metallic bristles. These features are shown and fully described in the aforesaid Patent #1,238,310, and therefore a full description and illustration of them need not be here repeated. Suffice it to say that the shaft 11 of the cylinder 36 is connected by gearing 21 with a short shaft 26 carrying a sprocket wheel 28 that is adapted to be driven by one of the belts or chains 17, Fig. 50 5. The chains also are utilized to drive the feed rollers 20, Fig. 18. It will be understood that the fiber being cleaned as it passes through the machine is carried between the elements of the several fiber cleaning groups, 55 that is to say, between the active cleaning element 29 on the one hand, and the rotary cylinder 36 on the other, such cylinder acting as a bed or support that holds the fiber material in proper position while being acted upon by the opposing element. As represented in Figs. 1, 2 and 3 the active fiber cleaning elements 29 are some of them located above the path of the fiber and some below such path, thus providing for the cleaning of the fiber from opposite sides.

The clamps for the leading ends of the fiber bearing masses to be treated in the machine, are designated, each as a whole, by 32, and one of them is illustrated in detail in Figs. 6, 7 and 8. It consists of a cross bar 70 or bed piece 33 of a length substantially equal to the width of the machine and preferably grooved or formed with a shallow channel in its upper face. This bar is preferably connected with trucks 37, the wheels 75 30 of which run on the tracks 14. I prefer that the trucks 37 should be separate from the cross bar 33 and united thereto by pivots 31 about which the trucks may turn to a limited extent for a reason that will presently be explained. A clamping bar 38 cooperates with the cross bar 33 to hold the fiber masses, it being arranged to come opposite to the recess or groove in the face of the cross bar and to force the material into such groove, thereby crimping it and giving to the clamp a secure grasp upon the material. The clamp bar is provided at its ends with arms 46 supported upon pivots 40 that project from brackets 42 rising from the cross bar 33. The arms 46 extend beyond the pivots 40 and are provided with contact projections 47. The upper surfaces of the trucks 37 are shaped to form lifting cams 50 whose functions will be later described. From the lower side of each truck 37 projects a finger 51, adapted to enter the open space of one of the links of the chain of the conveyor 3, and thus serving as a means by which the fiber clamp may be freely connected with the conveyor. In using the clamp the end of a piece of fiber bearing material intended to be cleaned by the machine is placed upon the cross bar 33, and the clamp 38 brought down, forcing the material into the recess of the cross bar securely clamping the material. A single piece of fiber material, or several of them, may be held in a single clamp, as the nature of the material being treated warrants. As has been stated, the clamp is connected with the conveyor 3, and thus temporarily made a part of the cleaning apparatus, by having its fingers engage with the opposite chains of such conveyor, the trucks of the clamp meantime rotating upon the tracks 14. While it is contemplated that the links of the two chains of the conveyor 3 at the opposite sides of the machine shall be in exact transverse alignment with each other, it sometimes happens that one chain has a slight lead over the other, making it difficult for the fingers 51 of the clamp to be simultaneously and properly engaged with links of the opposite chains, and when these fingers have been integral with the cross bars of the clamps, as has heretofore been the practice, much time has been lost in securing the proper engagement of the clamps with the conveyor chains that get out of alignment, for, as is understood, the clamps 125 130

are applied to the conveyor while it is in motion. It is for this reason that I make the trucks separate from the cross bars 33 of the clamp and unite them thereto by the pivots 31. The slight flexibility thus imparted to the clamp makes it possible to easily fit it to the moving conveyor whether the links in the opposite chains thereof be exactly opposite each other or slightly out of alignment. The clamp, being united with the conveyor, will be thereby carried through the machine, leading the fiber material with it, and in order that it may pass between the feed rollers 20, and between the revolving elements of the fiber treating groups, the shaft of each upper feed roller 23, and of each upper element of a fiber treating group, is provided with some means arranged to be engaged by the lifting cams 50 of the clamp bars to raise such upper rotating parts sufficiently to permit the clamps to pass between such opposed rotating parts of the machine. Thus there are rollers 53, Fig. 18, with which the cams 50 engage on the shafts of the upper feed rollers 23, and loosely mounted segments 34, with which the cams engage, on the shafts of the upper members of the fiber treating groups. The segments 34 are preferred to complete disks or rollers as they are lighter, and, being freely supported they are maintained by gravity in proper position to be acted upon by the cams 50 whenever they pass. These features are set out in the aforesaid Patent #1,238,310.

After the fibers have been sufficiently cleaned, by the brushes and other active cleaning elements, they are dried before being delivered from the machine, and in Figs. 1 and 4 the drying is represented as taking place in sections of the machine designated VII and VIII. Referring to these views 41, 41 designate air boxes, connected by a conduit 43 with a blast fan or other air moving device not illustrated. Above the air boxes are slotted supports 44 over which the fibers pass. This form of support is typical of any that may be used to properly hold the fibers while subject to the action of currents of air coming from the boxes 41. This air may be heated and dried, if found desirable, before being delivered against the material. There may be as many of these boxes as may be required in order that the cleaned fibers when they leave the machine shall be sufficiently dry to permit them to be inspected and packed.

In the use of my invention the material to be treated, for instance, the sheaths of the stems of abaca, are secured, preferably manually, in the clamps 32, and these are disposed in quantity at the head end of the machine, to which they are delivered by hand. I have provided automatic means to insure that the leading ends of one set of fibers shall follow closely after the rear end

of the preceding set has passed into the machine, and will now describe such means, referring particularly to Figs. 1, 3, 9, 10, 11, 12, 13 and 14.

45 represents a table at the feed end of the machine upon which clamps 32 carrying the masses of material to be treated are supported just preparatory to their entering the machine. 57 are guides for the clamps, carried by the frame pieces 58 of the head section of the machine, and arranged to direct the clamps, as they are pushed from the supporting table 45 and carry them into the desired proximity to the conveyor 3. Situated near the inner ends of the guides 57 are supporting platforms 59 onto which the guides direct the fiber clamp, the wheels of the trucks 37 resting thereon while the clamp is in position waiting to be connected with the conveyor and to be started on its journey through the machine. There is one of these platforms at each side of the machine, and they are supported in transverse ways 60 in which they slide. When a clamp is supported by the platform 59, as represented in Fig. 9, the fingers 51 of the clamp are held above the chains of the conveyor, which may therefore freely pass under the clamp without engaging therewith so long as it is thus supported. Whenever a clamp passes onto the platforms 59 the lifting cams 50 of the cam trucks pass under rollers 48 at the free ends of levers 61. These levers are acted upon by springs 62 that hold the levers against the clamps with a force that tends to move them downward or toward the chains of the conveyor; but so long as they rest on the platforms engagement between the clamp and chain cannot take place. I have, however, devised means for intermittently and simultaneously withdrawing the platforms from beneath the opposite trucks 37, leaving the clamp unsupported, which is thereupon instantly forced into engagement with the chains of the conveyor 3 by the spring-actuated arms 61. The mechanism for this purpose which I have devised and prefer to use is as follows. 49, 49 are bell cranks, one for each supporting platform 59. Each bell crank has two arms, 63, 64, the former connected with the platform, and the latter extending inwardly through the side frame piece 58 of the machine to a position to be acted upon by a cam 67. There are two of these cams 67, one at each side of the machine, and they are carried at the respective ends of a cone pulley 65 driven by the belt 27 referred to in discussing the driving gear arrangement shown in Figs. 1 and 3. The cam 67 is in the form of a ring carried by the cone pulley, at one of its ends. The face of the ring is, throughout about 270° of its circumference, concentric with the axis of the cone pulley, its remaining portion being ex-

centric with an abrupt drop at 69, as represented in Fig. 13. A roller 68 at the end of the arm 64 of the bell crank lever 49 engages with the cam 67, being held against such face by a spring 66. So long as the roller 68 is in engagement with the high, that is, the concentric, portion of the cam, the bell crank lever is held in position to maintain the platform 59 in the path of the truck of the clamp, the spring 66 being then under tension. But when the eccentric or low part of the cam comes opposite to the roller 68 the spring 66 moves the bell crank lever, carrying the platform outward and withdrawing it from below the clamp, which is thereupon forced into engagement with the conveyor 3, by the levers 61. The two opposite platforms should be withdrawn from below the fiber clamp simultaneously to permit the fingers 51 at the opposite ends of the clamp to engage with both chains of the conveyor 3 at the same instant. To insure this I secure to each cam ring a contact piece 70, Figs. 11 and 12, adapted to set into a recess in the face of the cam 67 and to extend across the drop 69. This contact piece is of hard metal so as to resist wear, and has a straight face 71. A second contact piece 72, also of hard metal, is carried by the arm 64 alongside the roller 68, and in position to engage with the contact piece 70 of the cam. The arrangement of these two pieces, 70 and 72, is such that when the straight edge of the contact piece 72 comes to the end of the contact piece 70 it moves along the straight face 71 of the latter with a quick drop, insuring the instant withdrawal of the platform from beneath the clamp. The cam thus terminates in an abrupt face 71 and these faces of the opposite cams can be brought into exact alignment with each other by adjusting the cam rings 67, each as a whole, or the contact pieces 70 with reference to their respective cams. The arms 63, 64 of the bell crank lever 49 might be integral; but I prefer that they should be separate and connected by the pivot on which the levers as a whole turn, and also by a spring 73 that holds the two parts of the lever together so that under normal conditions it acts as though of unitary construction. If, however, it should happen that an obstruction were in the path of a platform 59 at the time the high part of the cam engages a roller 68 of the bell crank lever the two-part construction of the lever described would permit the arm 64 to move, without a corresponding movement of the arm 63, the spring 73 yielding to permit this, see dotted lines, Fig. 9^a, so there would be no breakage of parts or straining of machinery. As soon as the obstruction just supposed has been removed the parts will be restored to normal relationship. The spring 73 is strong, as

compared with spring 66, insuring that the lever shall act as a unit under normal conditions.

For economy in operation it is desirable that the material being treated should be sorted so that that which is being treated at any one run of the machine should be of approximately the same length. It is therefore graded with this end in view preparatory to the starting of the machine, and this permits the use, to advantage, of the means for automatically starting the clamps through the machine, which has just been described. By shifting the belt 27 upon the cone pulley 65 the speed of rotation of the cam 67, with reference to the movements of the other parts of the machine, may be varied, and this adjustment is utilized when the length of the material being treated is changed. For instance, if the machine were set for treating masses of fiber of an average length of twelve feet, the pulley 65 would make a revolution at each twelve feet, and a little more, of linear movement of the conveyor 3, so that no sooner had the rear or following end of a mass of material passed into the machine than the clamp carrying the next mass of material to be treated would be started on its course through the machine. If now it should be desired to treat material of a different length, say eight feet, the belt 27 would be shifted upon the pulley 65 so as to cause one rotation thereof each time the conveyor 3 moved eight feet, and a little more; it being understood from the foregoing description that at each revolution of the pulley 65 a clamp is started through the machine.

After the fibers have been cleaned, and dried, when the machine is provided with a drying attachment as shown the fibers are automatically separated from the clamps and delivered from the machine, the clamps being either dropped or automatically returned to the head of the machine for use again. The mechanism for effecting this release of the cleaned fiber from the clamps is illustrated in Figs. 4, 15, 16, 17, 18 and 19.

At the delivery end of the machine, section IX, Fig. 4, is a pair of feed rollers 52. The lower of these is concentric with the sprocket wheels engaged by the chains of the conveyor 3 where they turn from their horizontal or working run to a vertical or downward course. It is just after this turn of the conveyor that the feed clamps are released. To effect this the side frame pieces 54 at the rear of the machine carry guideways 55 that, at their forward ends, join the rear ends of the tracks 14, and constitute ways along which run the rollers of the clamp trucks 37. These guideways 55 diverge from the path of the conveyor 3, so that the clamps are gradually separated therefrom, although they are still being posi-

tively moved forwardly for a certain distance before final separation takes place.

In order to release the ends of the fiber material from the clamp I mount wheels 57 upon the shaft of the upper roller 52, these wheels taking the place of the loose rollers 53 and the segments 34, heretofore described. Like the parts just referred to the wheels 77 are situated in the paths of 10 the lifting cams 50 on the trucks of the fiber clamps in order that they shall operate to lift the upper roller 52 sufficiently to permit the clamps to pass between these feed rollers without interference. The wheels 77 are 15 extra wide however, compared with the rollers or wheels 53, so that they not only lie in the paths of the cam 50 but also of the angular extensions 47 of the arms 46 of the movable bars 38 of the clamps. These extensions pass the rollers or wheels 53 and the segments 34 without engaging therewith, because of the location and of the narrowness of the latter, but they engage with the wheels 77, as is apparent from a comparison 20 of Figs. 18 and 19. The engagement between the contact extensions 47 and the wheels 77 automatically opens the clamp, releasing the fiber ends. As soon as the clamp fully escapes from the conveyor 3, 25 having then passed into the steep downwardly inclined portion of the guideway 55, it rapidly moves forward and downward, under the action of gravity, separating from the fibers and passing into the chute 6 that 30 delivers it to the returning conveyor 4 by which it is taken back to the head end of the machine. Meanwhile the fibers, now 35 separated from the clamp, are directed to the conveyor 7 by which they are delivered 40 from the machine where they may be removed by hand or by automatic machinery, as may be desired.

In order to direct the leading ends of the fibers to the conveyor 7 I have devised the 45 following mechanism: 79 designates a plate, of about the same width as the feed rollers 52, hinged along its edge close to the face of the lower of the said rollers. Springs 78 act on this plate and hold it free, that is, 50 rear, edge raised, as represented in Fig. 17, and in proximity to the receiving end of the conveyor 7. It thus constitutes a bridge between the final pair of feed rollers 52 and the conveyor 7 that operates to direct the fibers 55 and support them as they pass from the cleaning machine to the delivery conveyor. The plate 79 lies in the path of the fiber holding parts of the clamps 32 as they are directed by the guideways 55, and such 60 clamp parts, engaging with the plate depress it as they pass. While the plate is thus depressed the fibers lie upon its upper surface; but when the plate is restored to its normal position, by the springs 78, the fibers are 65 carried thereby into position to be engaged

by the delivery conveyor. A chain 74, or other equivalent flexible stop, serves to limit the extent to which the plate 7 may move upwardly.

It is very desirable that a machine such as 70 has been described shall be mobile, capable of moving to the location where the material to be treated grows, and of easily moving from place to place in said growing locality. In Figs. 20 and 21 I have illustrated the 75 cleaning machine as being supported upon a suitable structure frame 80 provided with a pair of caterpillar tractor devices 81 by which the machine may be moved from place to place over soft ground as well as upon substantial roadways; and these views are largely diagrammatic and represent an 80 installation of three cleaning machines, such as have been described, arranged side by side and designated respectively *x*, *y*, *z*, in Fig. 85 21. A suitable motor 82 is supported upon a platform on the structure frame and this is connected to a train of gearing 83 with the traction devices, and through another train of gearing 84 to the cleaning machines. 90 By means of suitable clutches 85 and 86 the application of power from the motor to either the traction device for propelling the apparatus, or to the cleaning machines for 95 operating them, may be controlled. The motor 82 may be of suitable construction, and the trains of gearing likewise of any suitable kind, and I have therefore indicated these parts diagrammatically. It will be 100 understood that other forms of tractor devices than a caterpillar structure may be employed.

The operation of the machine described will be understood from the foregoing 105 description. Several improvements which I have made and herein described produce a machine that is superior to any of which I have knowledge, in that among other things it is more nearly automatic and is devised so as to operate to the full capacity of the 110 machine and reduces to a minimum the requirements for manual co-operation.

What I claim is:—

1. In a machine for cleaning plant fibers, the combination with means for feeding the material through the machine and cleaning devices acting thereon during transit, of means for automatically starting through the machine the separate masses to be cleaned, and variable timing means arranged to operate the said starting mechanism with reference to the speed of the feeding devices.

2. In a machine for cleaning plant fibers, the combination with means for feeding the material through the machine, and cleaning devices acting thereon during transit, of means for automatically starting through the machine the separate masses of material to be cleaned, timed to operate with reference to the speed of the feed devices, and

means for varying the relative frequency of operation of the starting means.

3. In a machine for cleaning plant fibers, the combination with clamps for holding the leading ends of the fiber masses to be cleaned, a conveyor with which the clamps are made to engage for carrying them through the machine, and means for cleaning the material during transit, of intermittently acting means for causing automatic engagement of successive clamps with the said conveyor and means to vary the frequency of the operation of the said intermittently acting means with reference to the speed of the conveyor.

4. In a machine for cleaning plant fibers, the combination with a conveyor and fiber cleaning devices, of clamps separate from the conveyor but adapted to be engaged therewith and moved thereby, means for preventing engagement of the clamps with the conveyor, and means for operating the said preventing means and causing engagement of the clamps with the conveyor at regular intervals.

5. The combination stated in claim 4 and including variable timing means by which the frequency of the operation of the said preventing means to permit the engagement of the clamp with the conveyor, may be varied.

6. The combination stated in claim 4 including a guide for the clamps to direct them into co-operative engagement with the said preventing means.

7. In a machine for cleaning plant fibers, the combination with clamps for holding the leading ends of the fiber masses to be cleaned, a conveyor with which the clamps are made to engage for carrying them through the machine, and means for cleaning the material during transit, of means for holding a clamp in position adjacent to, but free from, the conveyor, and means for releasing the clamp from such holding means and causing it to engage with the conveyor.

8. In a machine for cleaning plant fibers, the combination with clamps for holding the leading ends of the fiber masses to be cleaned, a conveyor with which the clamps are made to engage for carrying them through the machine, and means for cleaning the material during transit, of means for holding a clamp in position adjacent to, but free from, the conveyor, automatic means for releasing the clamp from such holding means and causing it to engage with the conveyor, and means timed with reference to the speed of the conveyor for operating the automatic means.

9. In a machine for cleaning plant fibers, the combination with clamps for holding the leading ends of the fiber masses to be cleaned, a conveyor with which the clamps are made

to engage for carrying them through the machine, and means for cleaning the material during transit, of means for holding a clamp in position adjacent to, but free from, the conveyor, means for releasing the clamp from such holding means and causing it to engage with the conveyor, means for operating the said releasing mechanism timed with reference to the speed of the conveyor, and means for varying the timing of the said releasing mechanism.

10. In a machine for cleaning plant fibers, the combination with clamps for holding the leading ends of the fiber masses to be cleaned, a conveyor with which the clamps are made to engage for carrying them through the machine, and means for cleaning the material during transit, of a support for holding the clamp in position adjacent to but free from the conveyor, and means for withdrawing the support leaving the clamp unsupported and free to engage with the conveyor.

11. In a machine for cleaning plant fibers, the combination with clamps for holding the leading ends of the fiber masses, a conveyor comprising parallel chains, with which the clamps engage and by which they are carried through the machine, and means for cleaning the material during transit, of platforms at the opposite sides of the machine upon which a clamp may rest, serving to hold it adjacent to, but free from the conveyor, and means for simultaneously moving the platforms to release the clamp and permit it to engage with the chains of the conveyor.

12. A combination such as stated in claim 10 wherein the means for operating the platforms are bell crank levers operated by cams.

13. A combination such as stated in claim 12 in which the bell crank levers are divided and held together by a relatively strong spring that insures that the lever shall under normal conditions act as a unitary structure but may yield upon failure of the parts to function properly.

14. In a machine for cleaning plant fibers, the combination with clamps for holding the leading ends of the fiber masses, a conveyor with which the clamps are made to engage for carrying them through the machine, and means for cleaning the material during transit, of means for automatically releasing the fibers from the clamps after the cleaning operation arranged to act on the clamps to release them while in transit by the conveyor.

15. In a machine for cleaning plant fibers, the combination with clamps for holding the leading ends of the fiber masses, a conveyor with which the clamps are made to engage for carrying them through the machine, and means for cleaning the material during transit, of means for automatically separating

- ing the clamps from the conveyor after the fibers have been cleaned, comprising guideways engaged by the clamps, diverging from the path of the conveyor.
16. Mechanism such as described in claim 15, in which the guideways incline in a downward direction so that the clamps on being separated from the conveyor continue to move along the guideways by gravity.
- 10 17. In a machine for cleaning plant fibers, the combination with clamps for holding the leading ends of fiber masses, chains with which the clamps are made to engage, means for directing the chains through the machine 15 in definite paths, and means for cleaning the fibers, of means for causing the clamps while still being moved forward by the chains to gradually diverge from the path followed by the chains and hence separate 20 therefrom.
18. In a machine for cleaning plant fibers, the combination with clamps for holding the leading ends of the fiber masses, a conveyor with which the clamps are made to engage for carrying them through the machine, 25 and means for cleaning the material during transit, of means for automatically releasing the fibers from the clamps after the former have been cleaned, and means for automatically separating the clamps from the conveyor after the fibers have been released.
19. The combination stated in claim 15 including conveying means for directing the released clamps back toward the head end of the machine.
20. The combination stated in claim 14, including a conveyor for directing away from the cleaning machine the cleaned fibers after being released from the clamps.
21. The combination stated in claim 20, including a bridging means between the cleaning machine and the conveyor that leads away the cleaned fibers.
22. The combination stated in claim 21 in which the said bridging means are spring held in normal position to direct the fiber, and are adapted to yield to permit the clamps to separate from the fibers and then return to normal position.
